UNITED STATES PATENT OFFICE.

JOHN W. CAMERON, OF CHICAGO, ILLINOIS.

RAIL-JOINT LOCK.

1,116,239.

Specification of Letters Patent.

Patented Nov. 3, 1914.

Application filed December 23, 1913. Serial No. 808,309.

To all whom it may concern:

Be it known that I, JOHN W. CAMERON, a citizen of the United States, residing at Chicago, in the county of Cook and State 5 of Illinois, have invented certain new and useful Improvements in Rail-Joint Locks; and I do hereby declare the following to be a full, clear, and exact description of the invention, such as will enable others skilled 10 in the art to which it appertains to make and use the same.

This invention relates to rail joints and one of the principal objects of the same being to provide means for joining the 15 meeting ends of railway rails and to permit of a certain amount of expansion and contraction and at the same time to hold the meeting ends against displacement.

Another object of the invention is to provide a rail joint or lock which will hold the 20 meeting ends of the rails together and preventing the pounding of the rolling stock as the cars pass over the joints.

Still another object of the invention is to 25 provide a rail joint which will prevent the spreading or sinking of the rails at the joint.

These and other objects may be attained 30 by means of the construction illustrated in the accompanying drawings, in which,

Figure 1 is a top plan view of a rail joint and lock made in accordance with this invention, Fig. 2 is a side elevation and partial section of the same, Fig. 3 is a vertical sectional view taken on the line 3—3 35 of Fig. 2 looking in the direction of the arrow, Fig. 4 is a horizontal sectional view taken on the line 4—4 of Fig. 3, Fig. 5 is a detail perspective view of the rail and lock, the base flange of which is shown broken 40 away and in section, and Fig. 6 is a perspective view looking at the under side of the end of one of the rails.

Referring to the drawings the numerals 1 45 designate the railway rails and at their meeting ends these rails are each provided with a plain flat side 2 forming a continuation of the web 3 of the rail, and as shown in Figs. 3 and 4 somewhat enlarged. It is to be noted that both ends of the rails are 50 exact duplicates.

Formed in the base flange 4 of the rail at the end thereof is a transverse recess 5 and a vertical slot 6 extending from the tread surface through the enlarged portions 2 and 55 through the base flange 4 of the rail. The

rail splice or lock comprises a base portion 7 having upturned flanges 8 at the opposite sides thereof, which extend along the outer edges of the base flanges 4 of the rail. The base portion 7 is made of sufficient length to 60 rest upon three ties with the joint of the rails located centrally upon one of said ties as shown more clearly in Figs. 1 and 2. Projecting centrally from the base portion 7 is the splicing member 9 provided with 65 rounded ends 10, said splicing member being adapted to fit within the slot 6 in the ends of the rails and to permit a slight movement of the rail ends to compensate for the expansion and contraction of the rails. 70

As shown in Fig. 4 at 11 there is a space between the end of the splicing member 9 and the recess 6 and this space is to permit the rails to expand or contract by the effect of heat or cold. Extending across the base 75 portion 7 are rectangular ribs or projections 12, one of which is fitted in each of the recesses 5 in the base flanges 4 of the rail ends. It is to be noted that the recesses 5 are somewhat wider than the ribs or projections 12, the purpose being to permit a certain amount of play for expansion and contraction. 80

The manner of assembling the parts of the joint and lock may be briefly described 85 as follows: The base flange of the splicing member may be placed upon the three ties with the member 9 disposed above the central tie of the three and the rails may be seated vertically and connected to the splicing member in an obvious manner. 90

From the foregoing it will be obvious that my rail joint and lock will hold the rails against spreading or sinking and will prevent the pounding of the rolling stock as it 95 passes over the joint for the reason that the splicing member 9 extends flush with the tread surface of the rails and that the wheels in passing over the joint will first pass over the rounded end of the member 9 100 and will not pound at the meeting ends of the rails.

What is claimed is:—

A rail splice and lock comprising rails each having a vertical slot at the end 105 thereof, said slot extending through the head, web, and base flanges of the rails, and recesses extending across the under side of the base flanges of said rails, and a splice and lock member comprising a base having 110

transverse ribs adapted to engage said recesses and a vertical portion seated in the slots in the ends of the rails, said slots and recesses being somewhat greater in area than the transverse ribs and splicing member to permit expansion and contraction of the rails.

In testimony whereof I affix my signature in presence of two witnesses.

JOHN W. CAMERON.
